(57) **CLAIM**

We claim the ornamental design for a multi-function disinfectant, as shown and described.

DESCRIPTION

FIG. 1 is a top, front perspective view of a multi-function disinfectant, showing our new design in a closed configuration;

FIG. 2 is a bottom, rear perspective view of the multi-function disinfectant of FIG. 1;

FIG. 3 is a top view of the multi-function disinfectant of FIG. 1;

FIG. 4 is a bottom view of the multi-function disinfectant of FIG. 1;

FIG. 5 is a rear view of the multi-function disinfectant of FIG. 1;

FIG. 6 is a front view of the multi-function disinfectant of FIG. 1;

FIG. 7 is a right side view of the multi-function disinfectant of FIG. 1;

FIG. 8 is a left side view of the multi-function disinfectant of FIG. 1;

FIG. 9 is a top, front perspective view of a multi-function disinfectant, showing our new design in an open configuration;

FIG. 10 is a bottom, rear perspective view of the multi-function disinfectant of FIG. 9;

FIG. 11 is a top view of the multi-function disinfectant of FIG. 9;

FIG. 12 is a bottom view of the multi-function disinfectant of FIG. 9;

FIG. 13 is a rear view of the multi-function disinfectant of FIG. 9;

FIG. 14 is a front view of the multi-function disinfectant of FIG. 9;

FIG. 15 is a right side view of the multi-function disinfectant of FIG. 9; and,

FIG. 16 is a left side view of the multi-function disinfectant of FIG. 9.

1 Claim, 16 Drawing Sheets
